UNITED STATES PATENT OFFICE.

THEO GRAY, OF COLUMBUS, OHIO, ASSIGNOR OF ONE-HALF TO GEORGE BREWER, JR., AND WILLIAM V. BREWER, BOTH OF SAME PLACE.

INSECT-EXTERMINATOR.

SPECIFICATION forming part of Letters Patent No. 429,345, dated June 3, 1890.

Application filed March 6, 1890. Serial No. 342,923. (No model.)

To all whom it may concern:

Be it known that I, THEO GRAY, a citizen of the United States, residing at Columbus, in the county of Franklin, State of Ohio, have invented certain new and useful Improvements in Insect-Exterminators, of which the following is a specification, reference being had therein to the accompanying drawings.

10 This invention relates to certain new and useful improvements in insect-exterminators; and it has for its object, among others, to provide a simple, cheap, and efficient device of this character, composed of few parts, that 15 shall be perfectly safe in use, provision being made against explosion, the two parts—one the chemical-holder and the other the heater—hinged together with a suitable catch to hold them together.

20 Other objects and advantages of the invention will hereinafter appear, and the novel features thereof will be specifically defined by the appended claims.

The novelty resides in the peculiarities of 25 construction, as will be more fully herein-after described, shown in the drawings, and then particularly pointed out in the claims.

The invention is clearly illustrated in the accompanying drawings, which, with the letters of reference marked thereon, form a 30 part of this specification, and in which—

Figure 1 is a side elevation of my improved insect-exterminator. Fig. 2 is a vertical section through the same.

35 Like letters of reference indicate like parts in both figures of the drawings.

Referring now to the details of the drawings by letter, A designates the heater portion, which is formed of any suitable metal 40 and of any desired shape and size. It is provided with an alcohol-receptacle A', provided with a removable screw-threaded cap A², by means of which the fluid may be introduced. This cap has a wick-tube a passing through, which tube also passes through an air-chamber b, the exterior threads of which the cap engages, as shown in Fig. 2. This air-chamber prevents heating of the fluid within the reservoir. The top of the reservoir 45 has an opening for the passage of the

wick-tube, the metal around said opening being upturned, as shown in Fig. 2, to provide a sort of nipple to guide the tube and provide a better hold therefor. Suitable openings a' for the ingress of air to aid combustion are provided in the body of the heater portion, as shown, preferably at a point about on a level with the highest point of the top of the reservoir. Vent-openings b' should also be provided for the escape of gas and to prevent injury to the bottom of the chemical-holder, soon to be described.

B is the upper portion, which constitutes the chemical-receptacle. It has a convex bottom, as shown in Fig. 2. The adjacent edges of the two portions are beaded or rounded, as shown in Fig. 2, which allows them to turn on each other when desired, as when the upper part is thrown back to provide access to the burner. The portion B is hinged to the portion A by means of a suitable hinge C, formed preferably of wire, one portion secured to the lower portion A and bent outward at the upper end to conform to the curve of the rim, as shown in Fig. 2, and the other portion connected therewith in any suitable manner to form a hinge that will allow of easy movement of the parts. Opposite the hinge there is provided a catch to lock the parts together. It consists of a spring-arm D, attached at its 70 lower end to the lower portion A within its free end, bent to engage over the rim on the bottom edge of the upper portion B, and formed with suitable eye or thumb piece.

E is a keeper on the lower portion A, through 75 which the free end of the spring-arm passes and is guided, the said keeper being secured to the lower portion in any convenient manner.

F is a handle to the upper portion B, by which it may be handled and carried from 80 place to place when desired.

G is a removable cap to the chemical-receptacle, said cap being formed with a nipple g to receive one end of a flexible pipe H, the said nipple being inclined from a perpendicular, as shown, so as to hold the pipe from contact with the metal portions of the device, as will be readily understood. The other end of this pipe is provided with a metallic discharge-nozzle I, which is seated in a prefer- 85 90 95 100

ably wooden handle J, which prevents the hand from becoming heated during the use of the device. This handle is made easily removable to allow of the nozzle being inserted in cracks or crevices when desired.

The manner of use will be apparent. Alcohol or any other desirable fluid is placed in the lamp and water and chemicals in the upper receptacle. I employ aqua-ammonia and sometimes carbolic acid, and sometimes may dispense with the use of either, employing steam alone, but prefer to use either the aqua-ammonia or the carbolic acid, as I have found from experience that some insects can be killed much quicker when either the one or the other is used. The lamp being lighted, the heat creates steam within the chemical-receptacle, which gives pressure, so that it will be forced into and penetrate cracks or crevices into which the discharge end of the nozzle may be introduced. The flexible pipe, besides serving to convey the vapor to the cracks and crevices, serves also as a safety-valve and prevents explosions.

The device is simple, cheap, durable, and in practice has proved to be very efficient for the purpose for which it is intended.

What I claim as new is—

1. The combination, with the heater portion having reservoir, air-openings, and vents, of the receptacle arranged above the heater portion and hinged thereto and supported di-

rectly thereon and provided with vapor-conveying tube, substantially as described.

2. The combination, with the chemical receptacle having vapor-conveying tube, of the heater portion formed with fluid-receptacle, having an air-chamber on the top of the said receptacle, and a removable cap surrounding said air-chamber and carrying a wick-tube 35 passed therethrough, substantially as specified.

3. The combination, with the heater portion having fluid-reservoir, of the chemical-receptacle hinged to and resting directly upon 45 the heater portion, and a removable cap therefor provided with an inclined nipple and a flexible tube connected with said nipple, substantially as specified.

4. The combination, with the heater portion provided with fluid-reservoir and the chemical-receptacle hinged to and supported directly upon the same, of the cap to the chemical-receptacle, the flexible tube connected with said nipple, and the discharge 55 nozzle on said tube provided with a removable surrounding handle, substantially as specified.

In testimony whereof I affix my signature in presence of two witnesses.

THEO GRAY.
